UNITED STATES PATENT OFFICE.

DAVID A. SELIGMAN, OF PROVIDENCE, RHODE ISLAND.

PIN-TONGUE.

SPECIFICATION forming part of Letters Patent No. 763,805, dated June 28, 1904.

Application filed February 24, 1903. Renewed December 1, 1903. Serial No. 183,410. (No model.)

To all whom it may concern:

Be it known that I, DAVID A. SELIGMAN, a resident of Providence, in the county of Providence and State of Rhode Island, have invented 5 certain new and useful Improvements in Pin-Tongues; and I do hereby declare that the following is a full, clear, and exact description thereof, reference being had to the accompanying drawings, and to the letters of reference 10 marked thereon, which form a part of this specification.

This invention consists of certain improvements in pin-tongues for brooches, lockets, and the like, and has for its object the doing 15 away of the hinge-pivot, the facilitating of assembling of the parts, and replacing the pin-tongue when one has become broken.

It is fully described and illustrated in this specification and annexed drawings.

20 Figure 1 represents a side elevation of my improved pin-tongue as attached to the post which is in the back of a locket or brooch. Fig. 2 shows a plan view of the same with the pin turned at right angles to the brooch, in 25 which position the pin is best inserted into the goods. Fig. 3 is a detailed view of the pin, showing the coil at the end. Fig. 4 is an enlarged view illustrating the manner in which the coil of the pin engages the post. Fig. 5 30 is a side elevation showing the pin attached to a waist-lengthening plate. Fig. 6 is an enlarged view illustrating the manner in which the coil of the pin is attached to said waist-lengthening plate. Fig. 7 is a top plan view of the 35 plate and pin. Fig. 8 is an underneath view of the plate, showing the lower end of the coil projecting through the plate and resting against the under side thereof.

In the construction of my pin-tongue and 40 joint A is the plate or back of the brooch, at one end of which the post B is attached. This post has an eye or hold b through it at its upper end.

C is the catch, secured to the outer end of 45 the plate A.

My improved pin-tongue D may be constructed of ordinary spring-wire pointed at one end a and wound at its opposite end into an open spiral coil d. This coil may contain 50 as many turns as desired, preferably about

two turns, as shown in Fig. 3. To attach my pin-tongue to the plate, I simply pass the end d' of the coil d through the eye of the post B, turn the pin about once and a half around, and it is in position for the end a to be sprung 55 down and locked under the catch C.

In operating my device when attached to a brooch, as illustrated in Fig. 1, when I pass the end of the coil through the eye of the post and turn the pin around one of the coils 60 passes entirely around and rests against the post, which is cut out in front at b' to receive the coil, the end of which extends down and rests on the plate in the rear. This construction and manner of fastening holds the pin 65 firmly to the post and gives the proper elevation to the point above the catch C, the top coil giving the pin a very resilient and effective spring, one that is not easily set or broken and can readily be depressed and retained in 70 the catch. When it is desired to pass the pin through the goods in attaching the brooch to the garment, said pin may be turned out at right angles to the plate, as illustrated in Fig. 2, the plate thus forming a good handle by 75 which to insert and guide it, and when the pin is in place in the goods the plate is swung back and the point hooked under the catch C, where it is securely held by the resiliency of 80 the spring-coil. Should the pin be accidentally broken, as is often the case in this class of goods, a new one can easily be inserted in its place by unskilled hands and without the aid of tools, which is considered a very desirable 85 feature.

Figs. 5, 6, 7, and 8 are views showing my pin attached to a waist-lengthening hook. In these devices it is desirable to have the point of the pin lie close to the back of the hook-plate. This is accomplished by passing the 90 end of the coil d' to rest against the underneath side. This holds the pin securely in place, giving the point the proper downward pitch, the spring being given by the upper coil the same as in the brooch. This pin-tongue 95 is found to be very simple and practical in construction and efficient in its operation.

Having thus described my invention, what I claim as new, and desire to secure by Letters Patent, is—

1. In a device of the character described, a plate, a post on said plate, said post having a perforation or eye, a pin-tongue pointed at one end and having a coil on its opposite end, 5 said coil engaging the eye in said post for the purpose of holding the pin-tongue in place.

2. In a device of the character described, a plate, a post on said plate, said post having a perforation or eye, a pin-tongue pointed at 10 one end and having a coil on its opposite end, said coil engaging the eye or perforation in said post, the end of said coil projecting through the plate and engaging its under side for the purpose of holding the pointed end of 15 said pin-tongue in place against the back of the plate.

3. In a device of the character described, a pin-tongue constructed of spring-wire pointed at one end, a spiral coil formed at its opposite end, a brooch-plate, a post having a perforation or eye on the back of said brooch-plate, said coil engaging the eye in said post, one end of said coil projecting through said 20 plate and bearing on its under side to hold the point of the pin-tongue in position against the back of the plate.

4. In a device of the character described, a pin-tongue composed of spring-wire pointed at one end with a spiral coil at its opposite 25 end, a plate, a post on the back of said plate, an eye in said post said coiled portion pass-

ing through said eye and also around the post for the purpose of holding said pin-tongue in place.

5. In a device of the character described, a 35 plate, a pin-tongue pointed at one end and having a coil at its opposite end, means connected to said plate through which said coil may pass for the purpose of holding the pin-tongue in place.

6. In a device of the character described, a plate, a pin-tongue pointed at one end and having a coil at its opposite end, means including an eye connected to said plate through which said coil may pass to hold said pin-tongue in place. 40

7. In a device of the character described, a plate, a pin-tongue pointed at one end and having a coil at its opposite end, means including an eye connected to said plate through 45 which said coil may pass in combination with means for engaging the end of said coil to hold the pointed end of the pin in the desired position.

In testimony whereof I have hereunto set 55 my hand this 19th day of February, A. D. 1903.

DAVID A. SELIGMAN.

In presence of—

HOWARD E. BARLOW,
CHAS. P. DAY.
